DES. 1940

Elias Ingraham, of Bristol, Conn.
Letters Patent No 1940-Dated May 17, 1803.
Design for a clock case.

The schedule referred to in these Letters Patent and making part of the same.

To all whom it may concern:

Be it known that I, Elias Ingraham, of Bristol, County of Hartford and State of Connecticut, have invented or produced a new and original design for clock case; and I do hereby declare that the following is a full and exact description of the same, referring to the photographic illustrations, in which the same letters indicate like parts.

In the accompanying illustrations is shown a new and original design for a clock case.

A. is a plain square edge, and circular top frame or case, B. is a plain square edge base. The front edge of said case A is embossed with round circular arch C, and round ornamental columns D. E. is a recess surface configurated with moraled sashes F. G. and rosettes H. H. The whole combined to produce an ornamental design for a clock case.

What I claim and desire to secure by Letters Patent, is
The design for a clock case as above set forth and described.
